STEAM GENERATOR

Felix Holzknecht, Vancouver, British Columbia,
Canada

Application April 13, 1939, Serial No. 267,649

2 Claims. (Cl. 122—115)

This invention relates to steam generators and it consists in the constructions, arrangements and combinations herein described and claimed.

It is an object of the invention to provide a generator in which a down draft of fire through fire tubes is provided, reducing heat losses through trapping of lighter gases which ordinarily pass to the flue of a generator.

It is also an object of the invention to provide a generator in which there is no turbulence of the water being heated due to the down flow of fire through the fire tubes of the generator.

It is a still further object of the invention to provide a generator in which scaling of the boiler is eliminated, since the impurities are caused to pass to a mud sump in the base of the generator.

Additional objects, advantages and features of invention will be apparent from the following description considered in conjunction with the accompanying drawings, wherein

Figure 1 is a top plan view of the generator.

Figure 2 is a cross section on the line 2—2 of Figure 1.

Figure 3 is a top plan view of the float bearing employed in the generator.

Figure 4 is an enlarged detail of the relief valve.

Figure 5 is an enlarged fragmentary detail of the upper portion of the generator.

Figure 6 is a horizontal cross section through the generator.

Figure 7 is a cross section on the line 7—7 of Figure 1, and

Figure 8 is a diagrammatic view illustrating the electrical circuits for actuating water control valves and ignition means of the generator.

Referring to the drawings, there is illustrated a generator indicated by the reference character 10 which comprises an annular drum 11, the lower end of which is provided with a downwardly extended conical base 12, and the upper end is provided with an upwardly directed conical head 13. It should be noted that the drum 11 extends above the head 13, as indicated at 13'.

The base 12 and the head 13 are connected by a plurality of fire tubes 14, arranged in circumferential rows as clearly shown in Figure 6. The base 12 has a downwardly extended collar 15, internally threaded for reception of a sump valve 16. The head 13 has integrally formed therewith an upstanding collar 17, the latter being axially aligned with the collar 15. As may be seen from Figure 2, the innermost tubes 14 are positioned just outwardly of the peripheries of the collars 15 and 17, thereby providing a central unre-

restricted area 18 for a purpose as will appear hereinafter.

A casing 19 is fixed to the base 12, extending circumferentially therearound and includes a pipe 20, at the outer end of which there is suitably mounted an inductor blower 21, driven by means of a motor 22.

The tubes 14 open upon the casing 19 and it will therefore be seen that with the blower 21 in operation, a down draft through the tubes will be created, as will be dealt with in greater detail hereinafter.

Within the collar 17 there is snugly fitted a sleeve 23 having a plurality of inwardly directed radial fins 24, the lower ends of which are provided with stop means 25. If desired, the collar 17 may be recessed as at 26 for support of the sleeve.

Extended between a pair of fins 24 there is a bearing member 27 consisting of an axial bearing sleeve 28 from which oppositely extended arms 29 are provided, the latter being formed with forked ends 30 for engagement with respective opposed fins of the sleeve. The upper ends 25 of the fins 24 are provided with struck out tongues 31 preventing upward movement of the bearing member 27. Other stop means may be provided, however.

The bearing sleeve 28 reciprocately supports a stem 32, and upon the lower threaded end there is engaged a float 33. The float 33 may be adjusted upon the threaded stem to accommodate various desired water levels in the generator. The upper end of the stem terminates in a head 34 operable between a pair of electrical contacts, now to be described.

The upper end of the collar 17 is exteriorly threaded to receive a flanged collar 35, the latter being suitably apertured and tapped to receive the bolts 36 extended through apertures of a closure plate 37 for the collar 17. The plate 37 has an annular tapered flange 38 for seating engagement with a similarly formed seat of the upper end of the collar 17, whereby a steam-tight connection may be formed, it being understood that by tightening the bolts 36 draw the flange 38 into snug and tight engagement with the upper end of the collar 17.

The closure plate 37 has insulatedly mounted therein a pair of contacts 39 and 40, the first named affording control of the low level of water and the latter the high level of water within the generator, as will be apparent as the description proceeds, and reference is now made to Figures 5 and 8 of the drawings. It will be noted

that the contact 39 is positioned below the level of the contact 40, and that the head 34 of the stem of the float is movable upwardly and downwardly between the contacts and that the contacts will be engaged by the head in either of its extreme movements.

As may be seen in Figure 8, lowering of the float 33 will cause engagement between the contact 39 and the head 34 completing the electrical circuit to an electromagnet 41 for actuating a valve 42 associated with the inlet 43, admitting water to the pump 44 for passage to the generator 10, by way of a pair of branched contacts 45 discharging into a lower portion of the generator. The flow of water continues until the float 33 rises to such extent that the head 34 disengages the contact 39. However, should passage of water into the generator continue, through leakage or otherwise, the float will be caused to rise further, engaging the contact 40 when the electromagnet 46 is energized to actuate the bypass valve 47 which is normally closed.

The inlet conduits 45 will include one-way valves 46 admitting water to the generator 10, but opposing the return of water when the bypass valve is open. It will thus be seen that the water from the condenser line 48 will by-pass through the valve 47, the pipe 49 to the inlet side of the pump 44. This circulation of water is possible since the steam pressure in the generator 30 maintains the valves 46 closed to passage of water to the generator.

In the present instance, springs 50-50' retract the core of the electromagnets 41-46, and the electromagnets are energized through a source 35 51 through leads 52-53.

A relief valve 54 is mounted upon the elbow 55, the latter having a threaded nipple for connection of a pipe leading to the point of use. As shown, the elbow comprises an apertured flange 40 56 seated around a reduced nipple 57 of the elbow, the opposite end of the nipple having a tapered portion 58 complementary to a seat in the plate 37. The flange 56 has circumferentially spaced apertures through which tie bolts 59 are 45 extended, the latter being threadedly engaged in apertures 60 of the plate 37. It will thus be seen that the elbow 55 may be securely mounted against leakage of steam. The relief valve 54 comprises a spring-seated valve 54' and the 50 housing therefor preferably has downwardly opening vents 61.

At a suitable point above the upper wall 13 there is provided a lining 62 of fire brick or clay, the latter having a vertical wall 63 for anchorage to the upstanding wall 13' as clearly shown in Figure 2, the lining being extended upwardly at an angle abutting the sleeve 17. Thus a fire chamber 64 is provided immediately above the tubes 14.

Between the uppermost portion of the lining 62 and the junction of the sleeve 17 with the top wall 13, a plurality of heat absorbing fins 65 are provided, in the present instance being shown as having a collar 66 circumscribing the sleeve 17 and a right angular annular flange 67.

The fins 65 are arranged in superposed relation, permitting ready installation and preferably will be provided with a high polish and finish as will the lining 62, in order to obtain 70 advantage of all heat from the products of combustion.

A dead air space 68 is provided outwardly of the lining 62 by the provision of a cap 69 entirely enclosing the lining, the cap being her-

5 metrically sealed to the outer wall 13' as clearly shown in Figures 2 and 7.

An outer casing 70 encircles the generator and the top thereof, the casing being spaced therefrom and open at the bottom to permit air to space therearound and supplying air to the burner indicated at 71.

Preferably, the burner 71 will direct its flame at a tangent to the fire chamber 64 so that the flame will be caused to follow a path circumferentially above the tubes 14 insuring an even distribution of fire above the tubes, and to assist this action, an arcuate deflector plate 72 is fixed to the inner wall of the generator, being positioned slightly in advance of the inlet 72' of the burner.

Means for igniting the fuel initially is provided, in the form of a spark plug 73 suitably mounted in the walls defining the chamber 64, and as may be seen from Figure 8, the plug is electrically connected with the battery through a lead 74. A switch 75 is also connected in the lead 74, as is a high tension coil 76.

In use, fuel under pressure is supplied to the burner 71, being discharged into the chamber 64 where it is ignited by the spark plug 73 upon closing of the switch 75. After initial igniting of the fuel, the circuit to the plug is broken through manipulation of the switch, the fire continuing so long as fuel is fed to the burner. The inductor blower 21 being in operation, a suction is created in the tubes 14, drawing the flame downwardly therethrough and since water in the generator is in direct contact with the tubes, the water will be rapidly heated and generated into steam, the latter passing upwardly and outwardly through the elbow 55 to a point of use. It will be noted that the upper portion of the body of water will be first heated, effecting a quick generation of steam, and this also prevents turbulence of the water, permitting ready and quick deposit of sediment to the inclined base 12 where the sediment will discharge to the sump, valve 16. Obviously, since the sediment is quickly removed from the water, deposits on and scaling of the tubes 14 and the generator walls will be prevented.

When the water level in the generator has lowered to a point where replenishment is necessary this is effected through lowering of the float, as has already been explained, and similarly the float controls the closing of the supply of water to the generator.

While I have specifically described the generator, this is by way of illustration only, and I consider as my own all such modifications in structure as fairly fall within the scope of the appended claims.

I claim:

1. A steam generator comprising a boiler having side walls and a conically shaped lower head and a similarly shaped upwardly disposed upper head, a plurality of circumferentially spaced fire tubes connected between the upper and lower heads, said tubes being positioned to provide an unrestricted central area, water inlet means opening into the boiler, said upper and lower heads having an axial sleeve, a sump valve connected with the sleeve of the lower head, a steam outlet fitting connected with the sleeve of the upper head, a cap disposed above the upper head and connected with the walls of the boiler defining a combustion chamber, a plurality of annular fins on the sleeve of the upper head positioned within the combustion chamber, a sec-

ond cap with depending walls spaced from the first cap to provide an outer casing surrounding the generator and defining an air space, the casing being open at the base to provide passage of air therearound, said combustion chamber having a tangentially positioned fuel port in the first cap in communication with the space defined by the outer casing, a fuel burner operatively associated with the fuel port and said air space, an arcuate deflector plate in the combustion chamber whereby to deflect the flame from the burner circumferentially of the chamber, and an inductor blower operatively connected with the lower ends of the fire tubes whereby to draw the fire downwardly therethrough.

2. A steam generator comprising a boiler having side walls and a conically shaped lower head and a similarly shaped upwardly disposed upper head, a plurality of circumferentially spaced fire tubes connected between the upper and lower heads, said tubes being positioned to provide an unrestricted central area, water inlet means opening into the boiler, said upper and lower heads having an axial sleeve, a sump valve connected with the sleeve of the lower head, a 25

steam outlet fitting connected with the sleeve of the upper head, a cap disposed above the upper head and connected with the walls of the boiler defining a combustion chamber, a plurality of annular fins on the sleeve of the upper head positioned within the combustion chamber, walls forming a dead air space between the combustion chamber and the cap, an outer casing surrounding the generator but open at the base to provide a space for passage of air therearound, a fuel port tangentially opening upon the combustion chamber through said cap and in communication with the space defined by the outer casing, a fuel burner operatively associated with the fuel port and the air space, a deflector plate in the combustion chamber having an arcuate portion extended in the direction of the flame from said burner whereby to deflect the flame from the burner circumferentially of the chamber, a housing enclosing the lower ends of the fire tubes and an inductor blower operatively connected with the housing whereby to draw the fire downwardly through the tubes.

FELIX HOLZKNECHT.
